DUAL CONTROL SEPARATION OF GAS
AND OILJay P. Walker and Clarence O. Glasgow, Tulsa,
Oklahoma, assignors to National Tank Company,
Tulsa, Oklahoma, a corporation of Nevada

Application July 24, 1952, Serial No. 300,788

9 Claims. (Cl. 183—2.7)

1

This invention relates to new and useful improvements in dual control separation of gas and oil.

One object of the invention is an improved dual control for oil and gas outlet valves particularly adapted to tanks having separate accumulating chambers.

Another object of the invention is to provide a dual control involving an oil accumulating chamber receiving oil from a horizontal stratum and having liquid level responsive means connected with dual actuating means for a gas outlet valve and an oil outlet valve connected with said chamber, whereby an independent oil level is maintained in said chamber and fluid pressure in the chamber is built up sufficient to elevate the discharged oil to the stock tanks.

A further object of the invention is to provide a tank having means for establishing oil and water strata and carrying off water and an oil accumulating chamber separate therefrom, together with dual controlled valve means for discharging oil from the chamber and conducting it to the stock tanks and building up gas pressure in the chamber sufficient to elevate the oil to said stock tanks.

Still another object of the invention is to provide a dual control for a tank having an oil accumulating chamber and a gas space therein and diaphragm-motor oil and gas outlet valves in combination with a float in the chamber having operating connection with a pilot valve for controlling a supply of gas to the valves to open the oil valve and close or pinch the gas valve and build up a pressure in the chamber for expelling the oil.

A still further object of the invention is to provide an improved dual control wherein a tank is provided with an obstruction having a weir at its upper edge whereby a liquid stratum is maintained in the tank and liquid is caused to overflow to a lower level in an accumulating chamber which latter has a gas space above its liquid level, thus oil in overflowing or cascading from the upper stratum to the lower level is degassed under some conditions.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a longitudinal sectional view of a por-

2

tion of a tank equipped with a dual control valve means constructed in accordance with the invention,

Fig. 2 is a transverse, sectional view through the tank showing the water discharge means,

Fig. 3 is an enlarged elevation of the pilot valve and its actuator,

Fig. 4 is a transverse, vertical, sectional view of an upright separator having the dual control valve means,

Fig. 5 is a view, similar to Fig. 4 of a horizontal separator having the dual control valve means,

Fig. 6 is a view, similar to Fig. 1, showing a different application of the invention, and

Fig. 7 is a vertical, sectional view of the volume tank of the apparatus of Fig. 6.

This application is a continuation-in-part of our co-pending application, Serial No. 91,182, filed May 3, 1949, now abandoned.

20 In the drawings, the numeral 10 designates a horizontal tank which may be of the construction shown in the co-pending application of Jay P. Walker, Clarence O. Glasgow, and Alex W. Francis, Jr., filed March 23, 1949, Serial No. 83,054, owned by applicants' assignee, or of some other form. In the tank a filter section F is provided between two upright partitions 11 and 12, each occupying a complete transverse area of the tank and being perforated. The filtering section is completely filled with filtering material M, such as wood excelsior or suitable material.

A liquid overflow partition 13 terminates short of the top of the tank and its upper horizontal edge constitutes a weir 14, which determines the liquid level in the tank. The oil level is determined by the weir and the water level is determined by any suitable water outlet means, such as an outside syphon box 15 connected with the tank by a water leg 16 and containing an over-

flow nipple 17 which discharges into a water pipe 18. The longitudinal area above the oil level constitutes a gas space G. On top of the tank is a gas separator S which is connected with the gas space rearwardly of the partition 12, by means of a pipe 19 which may act as a gas equalizer or a gas conductor. A gas discharge pipe 20 leads from the separator.

The treater operates in any suitable manner so as to produce the water, oil and gas stratum as illustrated and this operation may be as set forth in co-pending application, supra. Since only oil overflows the weir 14, the chamber C, between the partition 13 and the end or head 21 of the tank, contains only oil and gas. An oil level is maintained in the chamber by a float 22,

which is much lower than the oil level, forward of the partition 13. An oil discharge pipe 23 leads from the lower portion of the head 21, well below the oil level in chamber C. A diaphragm-motor oil valve 24 of any suitable construction is connected to the pipe. This valve is periodically opened to discharge oil from the chamber and maintain the level therein. A diaphragm-motor gas outlet valve 25 is connected to the gas discharge pipe 20. These valves are both operated by means hereinafter described whereby dual control is set up.

Usually a horizontal treater is supported on the ground and since the inlet to the stock tanks is at a higher elevation than the oil outlet of the treater some means must be provided to elevate the discharged oil and deliver it to said tanks. An economical method is to employ gas pressure by means of dual control of the oil and gas outlet valves, whereby a pressure in the tank sufficient for this purpose may be maintained.

The float 22 is mounted on the end of an arm 26 which extends from a rigid connection with a rock shaft 27 journaled in a bonnet 28 suitably mounted on the head 21. The shaft extends through one side of the bonnet and has fastened thereon a lever 29 extending in the opposite direction to the arm 26. An adjusting link 30 pivotally connects the outer end of the lever with the plunger 31 of a vertically disposed pilot valve 32. A gas supply line 33 leads from the gas discharge pipe 20 to the upper portion of the valve. A gas feed line 34 leads from the medial portion of the valve to the diaphragm motor of the outlet valve 24. A pressure regulator 35 is connected in the supply line 33. A second gas feed line 36 branches from the line 34 and is connected to the diaphragm motor of the gas outlet valve 25.

The diaphragm motors of the valves 24 and 25 are of the adjustable spring type which are in common use in this art. When the float 22 is in its normal or middle position, as is shown in the drawings, the oil will be at a static or normal level. With the float in this position the springs of the diaphragm-motors are adjusted so that approximately 10 pound pressure per square inch will be carried in the tank, the lines and connections. So long as this pressure prevails, the oil outlet valve will remain closed and the gas valve will adjust itself to open, close or pinch the gas valve 25 so as to maintain said pressure.

It will be noted that the feed line 34 goes to the underside of the motor of the oil outlet valve 24; while the branch line 36 connects to the top side of the motor of gas valve 25. Thus when sufficient gas pressure is applied, the oil valve will be opened and the gas valve will be pinched or closed. When the float 22 is in its normal position the pilot valve will be closed or throttled to the point that not more than 10 p. s. i. (meaning pounds per square inch) gas pressure will be delivered to the valves. However, when the liquid level rises in the chamber C, the float will be elevated thus opening the pilot to increase the pressure of the gas supplied to the lines 34 and 36.

If the gas pressure is insufficient to elevate the oil to the stock tanks, the float rises still higher and the gas pressure is increased so the gas valve 25 is pinched or closed, whereby the gas pressure in the tank is built up to the point where the oil is discharged to the stock tanks and the float lowered. It is obvious that once the springs of the diaphragm-motors have been adjusted to the

desired static pressures, the operation thereafter becomes automatic. Of course, it is possible to adjust the spring of the gas valve so as to carry more than the pressure necessary to elevate the oil, because so long as the pilot valve 32 remains closed or is throttled, the oil outlet valve will remain closed.

This control is dependent upon an arrangement whereby the oil level is controlled entirely by the volume of oil accumulated in the chamber C, which means that said oil level is not subject to fluctuations such as would occur if the oil was carried on a body of water. The chamber C serves as a surge chamber and thus the overflow partition and weir 14 become important. The discharge of the oil from the tank is entirely independent of the operation of the treater or the volume of water handled. Further, the provision of the chamber C assures a substantial stabilization of the oil level in advance of the partition 13.

While we have shown diaphragm-motor valves it is obvious that other types may be used. The valves illustrated are arranged so that the outlet valve 24 will reach a full open position when the desired pressure is built up in the treater. The gas valve 25 has the dual function of both holding a predetermined pressure in the treater and building up a pressure sufficient to elevate the oil to the stock tanks. It is obvious that while the pipe 19 is primarily for equalizing pressures between the tank and separator, gas may flow through said pipe to the separator and escape by way of the pipe 20. While the invention has been described in connection with a horizontal emulsion treater, it is not to be so limited.

In Fig. 4, we have shown the invention in connection with a vertical tank or oil and gas separator. The details of the separator have been omitted. A stream of oil and gas and, in some instances, entrained water, is admitted through an inlet 40 and a gas discharge pipe 41 leads from the top of the tank 42. A downwardly inclined shield 43 extends across the tank and has a depending skirt 44, extending from wall to wall and forming with the wall of the tank, a flume 45.

The skirt 44 terminates short of the bottom of the tank and is spaced from an upright partition 46 extending from said bottom. This partition has a weir 47 at its upper edge. The space in advance or on the lefthand side of the partition 46 forms a receiving chamber R; while the space beyond said partition forms an accumulating chamber C'. Since the dual control mechanism is employed in this form, the same numerals are used in connection with the illustration. Drain pipes 48 lead from the bottoms of the chambers R and C' and connect with a manifold pipe 49 in which a cutoff valve 50 is connected. Since more or less water enters the tank through the inlet 40, such water will accumulate in the bottom of the chamber R and escape through the manifold pipe 49 and thus does not rise high enough to overflow the weir 47. Over a period of time, sediment may collect in the bottom of the chamber C' and may be drawn off through the connection 48 in the bottom of said chamber. The valve 48' permits withdrawal of water without draining chamber C'.

In Fig. 5 a horizontal oil and gas separator is illustrated. This separator includes a tank 51 having an inlet 52 at its forward end which inlet, discharges into a scrubber box 53 in the upper portion of said tank. The oil or oil and water are collected in the bottom of the tank. An upright

partition 54 causes the liquids to stratify and the top stratum which is oil to overflow a weir 55 along the upper edge of said partition into an accumulating chamber C'. For instance, a water drain similar to the drain 49 and 50 in Fig. 4 may be used to remove water from the vessel 51. The gas escaping from the box 53 flows between the elongate baffles 56 and is carried off by way of a discharge pipe 57. The gas is prevented from by-passing the baffles by a partition 58, which depends therefrom into the liquid stratum. The oil is discharged from the chamber through an outlet pipe 59. The valve 24 is connected in the pipe 59 and the valve 25 is connected in the pipe 57, the dual control being the same as in the other forms.

In Figs. 6 and 7 is illustrated the application of the invention to the type of emulsion treater, or other vessel, disclosed in the co-pending application of Jay P. Walker, Clarence O. Glasgow and Alex W. Francis, Jr., Serial No. 220,476, filed April 11, 1951, owned by applicants' assignee. In this modification, the treater vessel or tank 60 has a gas outlet (not shown) leading to a condenser, scrubber, or other gas receiving enclosure 61. Water is withdrawn from the tank 60 through a water outlet tube 62 while the clean oil overflows through a skimmer or weir box 63 and a pipe 64 to a volume tank or enclosure 65. The tank 65 drains through a heat exchanger 66 to the outlet pipe or oil discharge pipe 23 which leads to the oil valve 24, previously described. Certain of the other previously described elements are also employed and are numbered accordingly, the gas discharge pipe 20 leading from the enclosure 61 to the gas valve 25.

The volume tank 65 is provided with a float 67, or other suitable liquid level responsive device, which is operatively connected to the pilot valve 32. The latter valve is supplied with gas and operates the valve 24 and 25 as set out hereinabove.

The operation of the modification shown in Figs. 6 and 7 is substantially the same as the operation previously given. The clean oil overflows into the volume tank 65, raising the float 67, and accumulates until the float has been lifted enough to actuate the pilot valve 32. Operation of the latter causes closing of the gas valve 25 to build up the gas pressure in the tanks 60 and 65, and opening of the oil valve 24 to permit discharge of the oil to the stock tanks. In actual operation, the float and pilot valve normally stabilize at some intermediate position at which the gas valve is closed sufficiently to hold on the treater, or other vessel, a pressure adequate to flow the oil therefrom, and the oil valve is opened sufficiently to accommodate such flow under the pressure applied. As the flow of oil to the treater surges or decreases, the pilot valve is actuated to make appropriate adjustment in the positions of the gas and oil valves.

The foregoing description of the invention is explanatory thereof and various changes in the size, shape and materials, as well as in the details of the illustrated construction may be made, within the scope of the appended claims, without departing from the spirit of the invention.

We claim:

1. In combination, a single tank, an overflow partition in the tank defining a weir at its upper edge, an oil accumulating chamber defined by said partition and walls of the tank, water discharge means from the tank in advance of said partition, an oil outlet from the chamber on the other side of said partition, a gas separator con-
- 5 nected with the tank, a gas outlet from the separator, an oil level responsive element in the chamber below the weir, a diaphragm oil valve connected to the oil outlet, a diaphragm gas valve connected to the gas outlet, a pilot valve having inlet connection with the gas outlet, an actuating connection between the level-responsive element and the pilot valve, a gas outlet conductor leading from the pilot valve and connected with the gas outlet valve above its diaphragm for closing said valve and connected with the diaphragm of the oil outlet valve below its diaphragm for opening said oil outlet valve.
- 10 2. In combination, a single tank, an overflow partition in the tank defining a weir at its upper edge, an oil accumulating chamber defined by said partition and walls of the tank, water discharge means from the tank in advance of said partition, an oil outlet from the chamber on the other side of said partition, a gas discharge having connection with the tank, a float in the chamber, a pilot valve having a pressure fluid supply, an actuating connection between the float and the pilot valve, said float maintaining an oil level in the chamber below the weir, a diaphragm-motor gas valve connected to the gas discharge, a diaphragm-motor oil valve connected to the oil outlet, and pressure fluid conductors leading from the pilot valve to the gas valve above its diaphragm and to the oil valve below its diaphragm to close the gas valve and to open the oil valve.
- 15 3. In combination, a single tank adapted to contain water, oil and gas, an oil accumulating chamber in the tank having an oil level therein, the tank having means for retaining water and oil levels outside of said chamber, means for excluding the water from the oil accumulating chamber, said chamber having an oil inlet from the oil level of the tank, an oil outlet from the chamber, a gas outlet having connection with the tank, water discharge means from the tank exterior of the oil chamber, a float in the chamber, a pilot valve having a pressure fluid supply, an actuating connection between the float and the pilot valve, said float maintaining an oil level in the chamber, a diaphragm-motor gas valve connected to the gas outlet, a diaphragm-motor oil valve connected to the oil outlet, and pressure fluid conductors leading from the pilot valve to the gas valve above its diaphragm to close said valve to the oil valve below its diaphragm to open the latter.
- 20 4. In combination, a tank, an upright cross partition in the tank having an overflow along its top edge and dividing the tank into an oil and water stratifying section on one side of said partition and an oil chamber on the other side of said partition, water discharge means from the stratifying section, a main gas outlet pipe connected with the tank above the oil level therein, an oil outlet pipe connected with the chamber, below the oil level therein, a diaphragm gas valve connected in the gas outlet pipe, a diaphragm oil outlet valve connected in the oil outlet pipe, a pilot valve connected on its inlet side with the gas pipe in advance of the gas valve, a gas outlet line leading from the outlet side of the pilot valve and having branches connected with the gas valve above its diaphragm and connected with the oil valve below its diaphragm, whereby the gas pressure tends to close the gas valve and tends to open the oil valve, and a float in the oil in the tank having an actuator connected with the pilot valve.
- 25 5. In combination, a single tank, an overflow partition in the tank defining a weir at its upper edge, an oil accumulating chamber defined by said partition and walls of the tank, water discharge means from the tank in advance of said partition, an oil outlet from the chamber on the other side of said partition, a gas separator con-
- 30 6. In combination, a single tank adapted to contain water, oil and gas, an oil accumulating chamber in the tank having an oil level therein, the tank having means for retaining water and oil levels outside of said chamber, means for excluding the water from the oil accumulating chamber, said chamber having an oil inlet from the oil level of the tank, an oil outlet from the chamber, a gas outlet having connection with the tank, water discharge means from the tank exterior of the oil chamber, a float in the chamber, a pilot valve having a pressure fluid supply, an actuating connection between the float and the pilot valve, said float maintaining an oil level in the chamber, a diaphragm-motor gas valve connected to the gas outlet, a diaphragm-motor oil valve connected to the oil outlet, and pressure fluid conductors leading from the pilot valve to the gas valve above its diaphragm to close said valve to the oil valve below its diaphragm to open the latter.
- 35 7. In combination, a single tank adapted to contain water, oil and gas, an oil accumulating chamber in the tank having an oil level therein, the tank having means for retaining water and oil levels outside of said chamber, means for excluding the water from the oil accumulating chamber, said chamber having an oil inlet from the oil level of the tank, an oil outlet from the chamber, a gas outlet having connection with the tank, water discharge means from the tank exterior of the oil chamber, a float in the chamber, a pilot valve having a pressure fluid supply, an actuating connection between the float and the pilot valve, said float maintaining an oil level in the chamber, a diaphragm-motor gas valve connected to the gas outlet, a diaphragm-motor oil valve connected to the oil outlet, and pressure fluid conductors leading from the pilot valve to the gas valve above its diaphragm to close said valve to the oil valve below its diaphragm to open the latter.
- 40 8. In combination, a single tank adapted to contain water, oil and gas, an oil accumulating chamber in the tank having an oil level therein, the tank having means for retaining water and oil levels outside of said chamber, means for excluding the water from the oil accumulating chamber, said chamber having an oil inlet from the oil level of the tank, an oil outlet from the chamber, a gas outlet having connection with the tank, water discharge means from the tank exterior of the oil chamber, a float in the chamber, a pilot valve having a pressure fluid supply, an actuating connection between the float and the pilot valve, said float maintaining an oil level in the chamber, a diaphragm-motor gas valve connected to the gas outlet, a diaphragm-motor oil valve connected to the oil outlet, and pressure fluid conductors leading from the pilot valve to the gas valve above its diaphragm to close said valve to the oil valve below its diaphragm to open the latter.
- 45 9. In combination, a single tank adapted to contain water, oil and gas, an oil accumulating chamber in the tank having an oil level therein, the tank having means for retaining water and oil levels outside of said chamber, means for excluding the water from the oil accumulating chamber, said chamber having an oil inlet from the oil level of the tank, an oil outlet from the chamber, a gas outlet having connection with the tank, water discharge means from the tank exterior of the oil chamber, a float in the chamber, a pilot valve having a pressure fluid supply, an actuating connection between the float and the pilot valve, said float maintaining an oil level in the chamber, a diaphragm-motor gas valve connected to the gas outlet, a diaphragm-motor oil valve connected to the oil outlet, and pressure fluid conductors leading from the pilot valve to the gas valve above its diaphragm to close said valve to the oil valve below its diaphragm to open the latter.
- 50 10. In combination, a single tank, an upright cross partition in the tank having an overflow along its top edge and dividing the tank into an oil and water stratifying section on one side of said partition and an oil chamber on the other side of said partition, water discharge means from the stratifying section, a main gas outlet pipe connected with the tank above the oil level therein, an oil outlet pipe connected with the chamber, below the oil level therein, a diaphragm gas valve connected in the gas outlet pipe, a diaphragm oil outlet valve connected in the oil outlet pipe, a pilot valve connected on its inlet side with the gas pipe in advance of the gas valve, a gas outlet line leading from the outlet side of the pilot valve and having branches connected with the gas valve above its diaphragm and connected with the oil valve below its diaphragm, whereby the gas pressure tends to close the gas valve and tends to open the oil valve, and a float in the oil in the tank having an actuator connected with the pilot valve.
- 55 11. In combination, a single tank, an upright cross partition in the tank having an overflow along its top edge and dividing the tank into an oil and water stratifying section on one side of said partition and an oil chamber on the other side of said partition, water discharge means from the stratifying section, a main gas outlet pipe connected with the tank above the oil level therein, an oil outlet pipe connected with the chamber, below the oil level therein, a diaphragm gas valve connected in the gas outlet pipe, a diaphragm oil outlet valve connected in the oil outlet pipe, a pilot valve connected on its inlet side with the gas pipe in advance of the gas valve, a gas outlet line leading from the outlet side of the pilot valve and having branches connected with the gas valve above its diaphragm and connected with the oil valve below its diaphragm, whereby the gas pressure tends to close the gas valve and tends to open the oil valve, and a float in the oil in the tank having an actuator connected with the pilot valve.
- 60 12. In combination, a single tank, an upright cross partition in the tank having an overflow along its top edge and dividing the tank into an oil and water stratifying section on one side of said partition and an oil chamber on the other side of said partition, water discharge means from the stratifying section, a main gas outlet pipe connected with the tank above the oil level therein, an oil outlet pipe connected with the chamber, below the oil level therein, a diaphragm gas valve connected in the gas outlet pipe, a diaphragm oil outlet valve connected in the oil outlet pipe, a pilot valve connected on its inlet side with the gas pipe in advance of the gas valve, a gas outlet line leading from the outlet side of the pilot valve and having branches connected with the gas valve above its diaphragm and connected with the oil valve below its diaphragm, whereby the gas pressure tends to close the gas valve and tends to open the oil valve, and a float in the oil in the tank having an actuator connected with the pilot valve.
- 65 13. In combination, a single tank, an upright cross partition in the tank having an overflow along its top edge and dividing the tank into an oil and water stratifying section on one side of said partition and an oil chamber on the other side of said partition, water discharge means from the stratifying section, a main gas outlet pipe connected with the tank above the oil level therein, an oil outlet pipe connected with the chamber, below the oil level therein, a diaphragm gas valve connected in the gas outlet pipe, a diaphragm oil outlet valve connected in the oil outlet pipe, a pilot valve connected on its inlet side with the gas pipe in advance of the gas valve, a gas outlet line leading from the outlet side of the pilot valve and having branches connected with the gas valve above its diaphragm and connected with the oil valve below its diaphragm, whereby the gas pressure tends to close the gas valve and tends to open the oil valve, and a float in the oil in the tank having an actuator connected with the pilot valve.
- 70 14. In combination, a single tank, an upright cross partition in the tank having an overflow along its top edge and dividing the tank into an oil and water stratifying section on one side of said partition and an oil chamber on the other side of said partition, water discharge means from the stratifying section, a main gas outlet pipe connected with the tank above the oil level therein, an oil outlet pipe connected with the chamber, below the oil level therein, a diaphragm gas valve connected in the gas outlet pipe, a diaphragm oil outlet valve connected in the oil outlet pipe, a pilot valve connected on its inlet side with the gas pipe in advance of the gas valve, a gas outlet line leading from the outlet side of the pilot valve and having branches connected with the gas valve above its diaphragm and connected with the oil valve below its diaphragm, whereby the gas pressure tends to close the gas valve and tends to open the oil valve, and a float in the oil in the tank having an actuator connected with the pilot valve.
- 75 15. In combination, a single tank, an upright cross partition in the tank having an overflow along its top edge and dividing the tank into an oil and water stratifying section on one side of said partition and an oil chamber on the other side of said partition, water discharge means from the stratifying section, a main gas outlet pipe connected with the tank above the oil level therein, an oil outlet pipe connected with the chamber, below the oil level therein, a diaphragm gas valve connected in the gas outlet pipe, a diaphragm oil outlet valve connected in the oil outlet pipe, a pilot valve connected on its inlet side with the gas pipe in advance of the gas valve, a gas outlet line leading from the outlet side of the pilot valve and having branches connected with the gas valve above its diaphragm and connected with the oil valve below its diaphragm, whereby the gas pressure tends to close the gas valve and tends to open the oil valve, and a float in the oil in the tank having an actuator connected with the pilot valve.

5. The combination set forth in claim 4, with a pressure regulator in the inlet connection of the pilot valve with the gas pipe.

6. In combination, a tank adapted to contain oil, water and gas, an oil accumulating enclosure having an oil level therein, the tank having means for retaining water and oil levels outside of said enclosure, means for excluding the water from the oil accumulating enclosure, said enclosure having an oil inlet from the oil level of the tank, an oil outlet from the enclosure, a gas outlet having connection with the tank, water discharge means from the tank isolated from the oil accumulating enclosure, liquid level responsive means in the enclosure, a pilot valve having a pressure fluid supply, an actuating connection between the level responsive means and the pilot valve, said responsive means maintaining an oil level in the enclosure, a diaphragm-motor gas valve connected to the gas outlet, a diaphragm-motor oil valve connected to the oil outlet, and pressure fluid conductors leading from the pilot valve to that side of the diaphragm motor of the gas valve upon which the application of pressure fluid will close the gas valve and to that side of the diaphragm motor of the oil valve upon which the application of pressure fluid will open the oil valve.

7. In combination, a tank adapted to contain oil, water and gas, an oil accumulating enclosure having an oil level therein, the tank having means for retaining water and oil levels outside of said enclosure, means for excluding the water from the oil accumulating enclosure, said enclosure having an oil inlet from the oil level of the tank, an oil outlet from the enclosure, a gas outlet having connection with the tank, water-discharge means from the tank isolated from the oil accumulating enclosure, a float in the enclosure, a pilot valve having a pressure fluid supply, an actuating connection between the float and the pilot valve, said float maintaining an oil level in the enclosure, a diaphragm-motor gas valve connected to the gas outlet, a diaphragm-motor oil valve connected to the oil outlet, and pressure fluid conductors leading from the pilot valve to that side of the diaphragm motor of the gas valve upon which the application of pressure fluid will close the gas valve and to that side of the diaphragm motor of the oil valve upon which the application of pressure fluid will open the oil valve.

8. In combination, a tank adapted to contain oil, water and gas, an oil accumulating enclosure carried by the tank and having an oil level therein, the tank having means for retaining water and oil levels outside of said enclosure, means for excluding the water from the oil accumulating en-

closure, said enclosure having an oil inlet from the oil level of the tank, an oil outlet from the enclosure, a gas outlet having connection with the tank, water discharge means from the tank isolated from the oil accumulating enclosure, liquid level responsive means in the enclosure, a pilot valve having a pressure fluid supply, an actuating connection between the level responsive means and the pilot valve, said responsive means maintaining an oil level in the enclosure, a diaphragm-motor gas valve connected to the gas outlet, a diaphragm-motor oil valve connected to the oil outlet, and pressure fluid conductors leading from the pilot valve to that side of the diaphragm motor of the gas valve upon which the application of pressure fluid will close the gas valve and to that side of the diaphragm motor of the oil valve upon which the application of pressure fluid will open the oil valve.

9. In combination, a tank adapted to contain oil, water and gas, an oil accumulating enclosure external of the tank and having an oil level therein, the tank having means for retaining water and oil levels outside of said enclosure, means for excluding the water from the oil accumulating enclosure, said enclosure having an oil inlet from the oil level of the tank, an oil outlet from the enclosure, a gas outlet having connection with the tank, water discharge means from the tank isolated from the oil accumulating enclosure, liquid level responsive means in the enclosure, a pilot valve having a pressure fluid supply, an actuating connection between the level responsive means and the pilot valve, said responsive means maintaining an oil level in the enclosure, a diaphragm-motor gas valve connected to the gas outlet, a diaphragm-motor oil valve connected to the oil outlet, and pressure fluid conductors leading from the pilot valve to that side of the diaphragm motor of the gas valve upon which the application of pressure fluid will close the gas valve and to that side of the diaphragm motor of the oil valve upon which the application of pressure fluid will open the oil valve.
